UNITED STATES PATENT OFFICE.

MAYER REINFELD, OF ST. LOUIS, MISSOURI.

NON-REFILLABLE BOTTLE.

SPECIFICATION forming part of Letters Patent No. 748,885, dated January 5, 1904.

Application filed October 17, 1903. Serial No. 177,461. (No model.)

To all whom it may concern:

Be it known that I, MAYER REINFELD, a citizen of the United States, residing at St. Louis, State of Missouri, have invented certain new and useful Improvements in Non-Refillable Bottles, of which the following is a full, clear, and exact description, reference being had to the accompanying drawings, forming a part hereof.

10 My invention has relation to improvements in non-refillable bottles; and it consists in the novel construction of bottle more fully set forth in the specification, and pointed out in the claim.

15 In the drawings, Figure 1 is a middle vertical section of the bottle, partly in elevation, showing the parts in their normal position. Fig. 2 is an inverted view of the bottle, showing the valve open for the free efflux of the liquid. Fig. 3 is a horizontal section on line 3-3 of Fig. 1; and Fig. 4 is a sectional detail of the plug closing the hole in the bottom of the bottle.

The object of my invention is to construct 25 a bottle which it will be practically impossible to refill without detection after being once drained of its contents, the bottle in the first instance being filled through an opening in the bottom, which is subsequently closed 30 by a plug incapable under ordinary circumstances of removal by parties handling the bottle.

In detail the invention may be described as follows:

35 Referring to the drawings, B is the body of the bottle, and N the neck thereof, the mouth M of the latter being closed by a cork C in the usual way. Below the mouth M is formed an enlarged chamber 1 for the free play of a 40 (preferably) conical valve 2, which when in its closed position rests against an annular ledge or seat 3, formed in the neck, the valve being provided with a depending stem 4, which is secured to the middle portion of a 45 limiting head or bar 5. The latter is of a length as to engage the wall of the base of the neck when the bottle is inverted, the points of engagement determining the distance to which the valve 2 may drop from 50 its seat for the pouring position of the bottle. For the inverted position of the bottle

the liquid contents flows around the head 5, through the neck, past the valve, and out through the mouth of the bottle, as indicated by the arrows in Fig. 2. When the bottle is 55 set upright, of course the valve will gravitate back to its normal position, seating itself upon the ledge 3 and forming a tight joint through which no liquid can pass.

A bottle of the character here described is 60 filled through the bottom, and provision must be made to close the opening of said bottom through which the bottle is initially filled. This opening is closed by a plug composed of a metallic disk 6, carrying a central stem 7, 65 over which is passed a rubber or other resilient sleeve 8, terminating in a conical head 9. The end of the stem 7 is subsequently expanded or burred over the head 9, when the plug is completed. In inserting the plug into 70 the opening of the bottom the head 9 becomes compressed sufficiently to pass therethrough and when forced fully through the base of the head laps over the walls of the opening, as best seen in Fig. 1. The sleeve 8 fills the 75 opening, and the disk 6 is received by a depression formed in the bottom of the bottle and of sufficient depth to bring the outer face of the disk flush with the surface of the bottom, whereby the plug will be permanently 80 safe against any possibility of being gripped and withdrawn after once inserted. Of course the filling of the bottle is accomplished after the insertion of the outer cork C.

In practice the shank 8 of the rubber head 85 9 may be provided with a layer of suitable cement or adhesive 10, which will set and harden and insure a perfectly liquid-tight joint at that point.

I do not wish to be limited to the precise details of construction for the several parts, as these may be varied without departing either from the spirit or nature of my invention.

Having described my invention, what I claim is

95 In a non-refillable bottle having a body portion and a neck, a valve permitting the discharge of its contents through the neck for an inverted position of the bottle, the mouth of the bottle being adapted to be closed 100 for such inverted position for filling purposes, the bottom being provided with a suitable

opening, a depression surrounding said opening, and a plug having a terminal disk adapted to be received by said depression and a resilient head adapted to be forced through
5 the opening, the base of the head subsequently lapping over said opening and effecting a tight joint, substantially as set forth.

In testimony whereof I affix my signature in presence of two witnesses.

MAYER REINFELD.
